To all whom it may concern:

Be it known that I, Saul Sigel, a citizen of the United States, residing at Manchester, in the county of Hillsboro and State of New Hampshire, have invented a new, original, and ornamental Design for Stocking, of which the following is a specification, reference being had to the accompanying drawings, forming part thereof.

Figure 1 is a side elevation of a stocking, showing my new design.

The characteristic feature of the design comprises the superposed somewhat diamond-shaped figures arranged on the back of the stocking as shown, with their apices in juxtaposition and having their sides bowed inwardly.

I claim:

The ornamental design for a stocking, as shown and described.
